UNITED STATES PATENT OFFICE

GEORGE HENRY BURRUSS, OF COLORADO, TEXAS, ASSIGNOR TO COL-TEX REFINING COMPANY, OF COLORADO, TEXAS, A CORPORATION OF DELAWARE

PROCESS OF TREATING OIL AND REAGENTS

No Drawing.

Application filed December 12, 1928. Serial No. 325,659.

This invention relates to the treatment of hydrocarbon oil and particularly petroleum distillates whereby such oil may be sweetened and substantially freed of sulfur compounds which ordinarily may be of a corrosive nature and impart an objectionable odor to the oil. The invention also relates to a method of treating certain reagents and to a method of reconditioning sludges obtained during treatment of hydrocarbon oils for the purposes of sweetening and substantially de-sulfurizing said oils.

In general it may be said that this invention is an improvement over the so-called "doctor" treatment in which oils are sweetened by agitation with solutions containing litharge (lead monoxide) dissolved in an excess of alkali, followed by an application of free sulfur to facilitate the removal of oil soluble reaction products. Furthermore, the invention pertains to a method of utilizing sludges resulting from the so-called "doctor" treatment whereby a great saving is effected in reagents employed and the sweetening or refining operation may be carried out much more rapidly, thoroughly and economically.

An object of this invention is to provide a method for sweetening and refining hydrocarbon oils by which the consumption of reagents may be materially reduced.

Another object is to provide a method for repeatedly regenerating a treating medium in the refining and sweetening of hydrocarbon oil.

Another object is to provide a treating medium for oil which may be efficiently removed from the treated oil without leaving any substantial portion of either the medium itself or objectionable reaction products in the treated oil.

A still further object is to provide a method of using lead sulfide in the treating and sweetening of petroleum distillates.

Another object is to provide a method of treating and sweetening hydrocarbon oils whereby losses of oil caused by entrainment in the treating medium are eliminated.

A still further object of this invention is to provide a reagent for sweetening and re-

fining petroleum distillates by means of which such petroleum distillates may be substantially freed of sulfur compounds in an economical and rapid manner.

Other objects, advantages and uses of this invention will be apparent from the following detailed description of one preferred method of treating oils and of regenerating the treating medium.

In refining petroleum distillates of the naphtha, gasoline or kerosene type, the use of the so-called "doctor" treatment has often been resorted to particularly on what is known as "sour" oil so as to produce an oil having the greater portion of the sulfur containing constituents removed therefrom and to produce a sweet product as evidenced by a negative "doctor" test. In carrying out the customary "doctor" treatment the oils are intimately mixed with a sodium plumbite solution such as is produced when litharge is dissolved in a solution of an alkaline hydroxide, customarily sodium hydroxide. The chemical reaction involved in preparing this treating medium is apparently the following:

By adding the above solution to an oil, a considerable proportion of the impurities are precipitated in the form of a sludge but certain oil soluble lead compounds are formed which may remain in solution in the oil. In practically all cases it is necessary to remove such oil soluble compounds, and this is accomplished by adding free sulfur to the oil so as to precipitate the oil soluble impurities in the form of lead sulfide or other sulfides. This reaction using a typical mercaptan of a type which is ordinarily removed, for purposes of illustration may be expressed as follows:

Obviously other mercaptans of complicated structure would reflect a more intricate equation but the above expressed action apparently occurs in all events, the oil being sweetened by chemical changes in the "sour" constituents leaving the treating agent in the

form of a sulfide sludge in a solution of caustic.

This resulting sulfide sludge may be removed from the treated oil by settling and decantation but large quantities of oil are generally lost because the sulfide sludge is extremely flocculent and carries with it a considerable proportion of the oil. It is extremely difficult to separate such entrained oil from the sulfide sludge by ordinary settling methods. Furthermore even if the method is carefully regulated, the cost of reagents is relatively high and large quantities of litharge, often exceeding one pound per gallon of treated oil, have to be used.

The sulfide sludge, including lead sulfide, caustic solution, etc., is usually discarded although some attempts have been made to treat it for the recovery of litharge for purposes of re-using the same in the treating process. The recovery of litharge from lead sulfide sludge, while feasible in the laboratory sense and on a very small scale, includes complicated steps of decomposition by means of acids or calcining which make the process commercially unattractive and unused at the present time.

It has been found that the above described lead sulfide sludge as produced in a treating process of the type described hereinabove may be regenerated very readily and reused repeatedly for treating oils, provided said regeneration is carried out in accordance with the process as hereinafter described. In view of the fact that the sludge may be used repeatedly as the source of treating agent, the requirements of reagents per unit of treated oil may be very materially reduced. Furthermore, the treating agent obtained by regenerating the lead sulfide sludge results in a process of treating oils which has numerous advantages over the treatment of oils with fresh reagents in accordance with present methods. For example, the treating medium obtained by regenerating the lead sulfide sludge in accordance with this invention is capable of rapidly separating from the oil treated therewith so that the loss of oil by entrainment is substantially eliminated and the period of settling materially reduced thereby not only saving oil but speeding up the operation and permitting a specific apparatus used in the treatment to handle a much larger volume of oil within a given time.

In general, the process of revivifying or regenerating the spent treating agent or sulfide sludge resulting from the litharge, caustic and sulfur treatment of oil, that is the "doctor" treatment, involves the agitation of such solution with its accompanying caustic solution in the presence of air and fresh litharge. The invention may be fully understood by reference to the following description of a typical case in which the initial

oil treatment by means of the "doctor" solution, the regeneration of the spent treating medium and the subsequent use of such regenerated treating medium is described.

A petroleum distillate may be first treated by agitation with a solution of litharge and caustic soda (sodium plumbite) such solution being generally about 18° Baumé, and a sufficient quantity of free sulfur, generally flowers of sulfur, added to the mixture to produce a sweet product as evidenced by a negative "doctor" test. The spent solution containing the sulfide sludge may then be drawn off and settled. It will be found that the sludge contains a large quantity of entrained oil and is of a very flocculent nature at first, but upon standing it changes from its original bulky mass to a dense powder-like material from which much of the originally treated oil may be skimmed leaving the sludge suspended in a solution of caustic.

After the liberated oil has been removed from suspension of lead sulfide in the alkaline solution, fresh litharge may be added in the proportion of about one pound of litharge per hundred gallons of sludge and solution. This mixture is then blown with air, oxygen or oxygen containing gases for about ten to fifteen minutes after which it is ready for use as an agent for further treating of petroleum distillates. The step of air blowing is essential but as has been stated above oxygen or oxygen containing gases may be used instead of air and various oxidizing compounds such as potassium permanganate and the like may also be used.

A fresh batch of petroleum distillate requiring refining and sweetening treatment may then be treated with the mixture prepared in the above described manner, ten to fifteen percent by volume of this mixture being added to the distillate and intimately mixed therewith. Free sulfur in the proportion of about one pound per five hundred gallons of a petroleum distillate of the gasoline type is then added to the oil and the entire mass agitated until the desired product as evidenced by a negative "doctor" test is obtained. When the required sweetness of product is attained, the solution containing sulfide sludge is drawn off, agitated with litharge and air blown as before and the cycle repeated. It has been found that the original sludge may be used a great number of times without impairment of its treating value and with an increasing efficiency in the facility with which the treating solution separates from the oil.

It is to be understood that the proportions of ingredients used will vary according to the character of the oil treated and the results required, but in any event a material saving is accomplished over other processes as indicated by the following results obtained by:

(A) treating a particular gasoline with

sodium plumbite solution followed by sulfur (customary "doctor" treatment);

(B) treating the same type of gasoline with sulfide sludge air blown in the presence of the gasoline being treated; and

(C) treating the same character of gasoline with sulfide sludge reconditioned according to the present invention described above.

10 *Materials required—lbs. per bbl. (50-gals.) gasoline*

Material	A	B	C
Caustic	6.41	4.28	1.29
Litharge	1.58	1.05	0.371
Sulfur	0.417	0.278	0.164

15

It is believed that the entire lead content of the original treating solution is recovered from the sulfide sludge in reactive condition except for mechanical losses, however, it has been found after repeated treatments its treating value may become impaired, probably due to its being masked by accumulations of foreign matter. The spent lead sulfide may then be steamed, washed or filtered to restore 25 its reactive power or it may be burned or otherwise treated to recover its valuable ingredients.

20 While a particular source of the lead sulfide sludge has been described, the invention may be applied to lead sulfide produced by the reaction of sodium sulfide and "doctor" solution or to other lead sulfides naturally or artificially produced.

25 Furthermore, the invention is not limited to a suspension of sulfide in caustic soda, other alkalis such as potassium hydroxide, soda ash and the like being suitable.

30 The invention may be broadly described as the production and use of a treating agent for hydrocarbon oils, derived from the reaction of lead sulfide and litharge with oxygen in the presence of an alkali, and while no claim is made as to the exact chemical process involved, it is thought that the reaction is in 45 accordance with the following equation:

35 It is to be understood that the treating agent obtained in accordance with the hereinabove described process is preferably maintained at a proper alkaline strength of 10° to about 18° Baumé equivalent. To maintain such alkalinity it may be desirable to add 40 caustic, in solid or concentrated liquid form, to the suspension of lead sulfide either before, during or after the addition of litharge and either before, during or after agitation with an oxygen containing gas.

45 While particular ingredients and proportions have been here specified for the purpose of illustration, it is understood that the invention is not so limited, the intention being to cover all variations within the broad scope of the following claims.

I claim:

1. A method of refining oils comprising adding litharge to a suspension of lead sulphide in an alkaline solution, oxidizing the mixture, adding the oxidized mixture to oil to be refined with agitation, then adding sulphur to said oil, and then separating the oil from the resulting suspension of lead sulphide in alkaline solution. 76

2. A method of refining hydro-carbon oils comprising adding litharge to a suspension of lead sulphide in alkaline solution, blowing an oxygen containing gas through the mixture, adding the oxidized mixture to oil to be refined with agitation, then adding sulphur to said oil, and then separating the oil from the resulting suspension of lead sulphide in alkaline solution. 80

3. A method of refining hydro-carbon oils comprising adding litharge to a suspension of lead sulphide in caustic solution, oxidizing the mixture, adding the oxidized mixture to oil to be refined with agitation, then adding sulphur to said oil, and then separating the oil from the resulting suspension of lead sulphide in caustic solution. 85

4. A method of refining hydro-carbon oils comprising adding litharge to a suspension of lead sulphide in a caustic solution, blowing an oxygen containing gas through the mixture, adding the oxidized mixture to oil to be refined, then adding sulphur to said oil, and then separating the oil from the resulting suspension of lead sulphide in caustic solution. 95

5. A method of refining petroleum distillates comprising adding litharge to a suspension of lead sulphide in an alkaline solution, blowing an oxygen containing gas through the mixture, adding the oxidized mixture to oil to be refined, then adding sulphur to said oil, and then separating the oil from the resulting suspension of lead sulphide in alkaline solution. 100

6. A method of refining petroleum distillates comprising adding litharge to a suspension of lead sulphide in a caustic solution, blowing an oxygen containing gas through the mixture, adding the oxidized mixture to oil to be refined, then adding sulphur to said oil, and then separating the oil from the resulting suspension of lead sulphide in a caustic solution. 110

7. A method of treating suspensions of lead sulphide in alkaline solution for use in refining oils comprising adding litharge to a suspension of lead sulphide in an alkaline solution, and then oxidizing the mixture. 120

8. A method of treating suspensions of lead sulphide in alkaline solution for use in refining oils comprising adding litharge to a suspension of lead sulphide in an alkaline solution, and then blowing an oxygen containing gas through the mixture. 125

9. A method of treating suspensions of lead sulphide in alkaline solution for use 130

in refining oils comprising adding litharge to a suspension of lead sulphide in an alkaline solution in the proportions of about one pound to one hundred gallons of said suspension, and then blowing an oxygen containing gas through the mixture.

10. A method of refining hydro-carbon oils which comprises agitating oil with litharge in caustic solution and adding sulphur, separating the refined oil from the sulphide sludge thus produced, adding litharge to the sludge, blowing an oxygen containing gas through the sludge, agitating fresh oil to be treated with the treated sludge and adding sulphur, and then separating the treated oil from the sulphide sludge thus produced.

11. A method of refining hydro-carbon oils comprising agitating the oil with litharge in caustic solution and adding sulphur, separating the treated oil from the sulphide sludge thus produced, allowing the sulphide sludge to settle, removing additional oil from the settled sludge, adding litharge to the sludge and blowing an oxygen containing gas through the mixture, agitating fresh oil with the treated sludge thus produced and adding sulphur, and then separating the treated oil from the sulphide sludge resulting from the last step.

30 12. A treating agent for hydro-carbon oils derived from the reaction of lead sulphide, litharge and oxygen in the presence of alkali and capable of producing a sludge readily separable by settling when mixed with an oil to be treated.

Signed at Colorado, Texas, this 26th day of November, 1928.
